UNITED STATES PATENT OFFICE.

JARRETT B. WOOD, OF TULSA, OKLAHOMA.

STEAM BOILER.

Application filed June 18, 1927. Serial No. 199,710.

This invention relates to new and useful improvements in steam boilers of the flash type that is wherein the steam is instantly generated upon the contact of the water upon 5 the hot plate of the boiler and that is arranged directly above a suitable burner or heat producing device.

In carrying out my invention there is provided a highly novel, simple and relatively 10 inexpensive steam boiler wherein steam may be rapidly and inexpensively generated and wherein the boiler is equipped with superheating coils arranged in spaced relation around the interior of the boiler.

15 In the drawings wherein like reference characters indicate corresponding parts throughout the several views:

Figure 1 is a detail vertical section through my improved boiler, and

20 Figures 2 and 3 are horizontal sections taken substantially upon the lines 2—2 and 3—3 of Figure 1.

Now having particular reference to the drawings, 5 designates a cylindrical jacket 25 open at its opposite ends and within which ends are arranged upper and lower manifold heads 6 and 7. The upper head 6 comprises a pair of spaced circular walls 7^x and 8 formed at their edges with downwardly extending flanges 7' and 8', the lower wall being arranged within the flange 7' of the top wall 7^x and said flanges being interconnected and anchored to the upper end of the jacket 5 by rivets 9.

35 The lower manifold head consists of inner and outer circular walls 10 and 11 which are also flanged as at 10' and 11', the lower wall 11 being arranged within the flange 10' of the inner wall 10 while both of said walls are 40 arranged within the lower end of the jacket 5 and their flanges interconnected and connected to the lower edge of the jacket by rivets 12. The inner walls 8 and 10 of the heads 6 and 7 are formed centrally with enlarged 45 circular openings within which are arranged and secured the opposite ends of a steam tube 13. Arranged upon the outer sides of the

outermost walls 7 and 11 of the heads 6 and 7, respectively, are reinforcing plates 13^x and 14, said outer walls being interconnected and braced by long stay bolts 15, the ends of which project through the plates 13^x and 14 and are headed as at 16.

Arranged at spaced points between the jacket 5 and steam tube 13 are vertical steam superheating coils 17 the opposite ends of 55 which have communication with the interior of the heads 6 and 7 of the boiler. Furthermore arranged through the walls 10 and 11 of the lower head 7 are flues 18 to permit the 60 products of combustion from a burner or flame beneath the boiler to pass into the boiler between the jacket 5 and said steam tube 13 with the result that the steam passing 65 through the coils 17 will be superheated.

A suitable inlet for the water and an exhaust for the steam are provided, the same being designated by the reference characters 19 and 20, respectively. Apertures 21 in the casing 5, afford outlet for the products of 70 combustion.

Having thus described the invention, what I claim as new is:—

In a boiler of the character described, an open ended jacket, a steam manifold located within the upper end of the jacket, a water manifold located within the lower end of the jacket, said manifolds each consisting of inner and outer plates spaced apart and having lapped flanges connected together 75 and to the jackets, a tube arranged intermediate the inner walls of said manifolds and having communication at its opposite ends with the interiors of said manifolds, heat flues extending between the walls of 80 the water manifold, steam coils arranged between the inner walls of the manifolds and having communication therewith, plates arranged at the outer sides of the outer walls 85 of the manifolds, and stay bolts extending 90 through the said manifold connecting tubes and connected to said plates.

In testimony whereof I affix my signature.

JARRETT B. WOOD.
